UNITED STATES PATENT OFFICE

ROBERT J. COPELAND, OF TORONTO, ONTARIO, CANADA

LOOSE LEAF BINDER

Application filed April 1, 1930, Serial No. 440,785, and in Canada April 4, 1929.

The principal objects of this invention are to provide a simple form of metal for the post type of binder which will lock securely in position by engagement with the post.

The principal feature of the invention consists of the novel construction of a sliding binder member within the adjustable metal or back which will slide longitudinally to move a pair of bevelled spring fingers into gripping engagement with each post.

In the drawing, Figure 1 is a perspective view of a binder back to which my invention has been applied.

Figure 2 is a perspective view with the top portion of the upper metal removed showing the sliding member in position engaging the post.

Numerous forms of slidable locks for holding binder backs in position on the posts have been devised, but many objections to these are found in that they work loose in the handling of the books or they fail to function properly in gripping the post.

According to the present invention the tubular metal 1 of the upper cover is provided with holes 2 through which the posts 3 extend and a longitudinal slot 4 is arranged therein between the posts.

Within the tubular metal is arranged a slidable bar 5 which is preferably formed with the upturned edge flanges 6 which form guides in the sliding of said member within the metal 1, the flanges snugly engaging the inner wall of said tubular metal preventing side to side movement of the bar 5 therein.

A slot 6' is cut in the flat bottom 7 of the bar 5 adjacent to one end and a notch 8 is cut in the opposite end of the bar, though the latter notch may be a slot similar to the slot 6' if desired.

The spring members for gripping the posts 3 are each formed from a sheet of metal having a cross-piece 9 at one end holding a pair of fingers 10 spaced apart said cross-piece being secured to the slide bar 5.

The inward edges of the fingers 10 converge toward each other and at the wider end permit the posts 3 to pass therebetween freely but they are so spaced that a slight

longitudinal movement of the bar 5 will bring the convergent edges of the fingers into contact with the posts.

The inward edges 11 of the fingers are turned in an upward and inward sloping direction and the plates from which the fingers are made are cut away in an outward direction adjacent to the cross piece 9 imparting torsional freedom and pronounced flexibility thereto so that the edges 11 will be free to spring in an upward direction throughout their entire length.

These gripping members are formed of thin sheet-metal stamped to shape and are tempered to a steel spring quality, consequently they will flex readily when moved into contact with the posts and will return to their normal position when moved out of contact.

In the center of the slide bar 5 there is formed a raised projection 12 to which the button 13 on the outside of the metal 1 is secured through the slot 4. By placing the finger and thumb on the button 13 the bar 5 may be moved longitudinally within the metal 1 to engage or disengage the posts.

The peculiar formation of the spring fingers 10 is such that if the slide bar 5 becomes displaced from its free position and a person places the top metal over the posts when such side bar is in such a position, no harm will be done to the locking member because the fingers will spring freely away from the posts because of their upward and inward slant.

The fingers are supported along their outer edges by fitting snugly into the angle of the slide bar 5 formed by the upturned edges preventing lateral bodily displacement of the fingers due to the thrust or expanding influence imparted thereto on engagement with the posts.

This feature of supporting the slender spring features at their outward edge is important and ensures that the fingers will not be distorted or injured and any movement thereof will be of a torsional nature providing a very positive and dependable locking condition, and since the sliding bar member is definitely confined against lateral dis-

placement within the tubular metal due to the contacting side flanges 6 engaging the side walls thereof, it will be evident that the locking of the fingers 11 with the respective posts will maintain the tubular metal back in a definitely locked position on the posts.

It will be seen that these spring finger members may be made very simply at low cost and the number of operations required 10 to make them and place them on the bar 5 and the construction of the bar 5 are all so simple that the cost will be reduced to the minimum.

What I claim as my invention is:—

15 1. In a loose leaf binder, the combination with the binder posts, of a tubular metal adapted to fit over said posts and having openings therethrough to receive the posts, a flanged bar slidably arranged within said 20 metal having slots through which said posts extend, and a pair of spring plates, each slotted longitudinally from one end, the latter slots having converging sides, the fingers formed by the slotting of said members resting within the angle of the flanged bar, said fingers being set with an upward and inward slope.

2. In a loose leaf binder, the combination with the binder post, and a binder metal having 30 openings to receive the post, of a gripping member arranged in said binder metal having a pair of fingers adapted to straddle the post, said fingers having converging edges inclined upwardly means for moving said gripping member longitudinally, the metal at the connected ends of said fingers being cut outward and away from the converging edges to weaken said fingers and impart 35 torsional freedom and flexibility thereto, and means engaging said weakened fingers at the outward edges to reinforce the same against outward thrust.

3. In a loose leaf binder, the combination with the binder posts, of a tubular metal 45 pierced to fit over said posts, a bar housed in said tubular metal said bar having slots to receive the posts and presenting a laterally turned flange at each side snugly engaging the wall of said tubular metal to limit lateral 50 movement of said bar, and spring locking fingers secured to said bar and movable by the latter into locking and unlocking relation to said posts, said laterally turned flanges co-operating with said spring fingers to support 55 the same in locking relation to said posts.

ROBERT J. COPELAND.
